UNITED STATES PATENT OFFICE.

HARRY S. HART, OF CHICAGO, ILLINOIS.

MAXIMUM-CAPACITY CAR.

Application filed July 28, 1924. Serial No. 728,532.

The present invention relates to railway cars designed for carrying and depositing ballast material which cars are also capable of use for commercial lading, such as coal 5 and the like.

The material used for ballasting track is heavier than commercial lading such as coal so that a car which is designed for carrying ballast material is usually of less cubic 10 capacity than a car designed for carrying commercial lading. The reason for this is, that the lading of ballast reaches the limit of weight allowable to be placed upon the axles with less cubic capacity than that of 15 commercial lading. It is desirable, however, in many instances, that a car should be capable of carrying the allowable weight of material either as ballast or as commercial lading such as coal. Further, ballast 20 materials of different weights occupy more or less cubic capacity so that it is desirable that a car be capable of carrying such ballast materials to the allowed capacity of the axles.

25 The object of my invention, therefore, is to provide such a car and also to provide a car from which either ballast material or commercial lading may be efficiently discharged.

30 Further objects will appear as the description proceeds.

Referring to the drawings—

Figure 1 is a longitudinal sectional view of a railway car embodying the principles 35 of the present invention; and

Figure 2 is a transverse sectional view, on a reduced scale, taken along the plane indicated by the arrows 2—2 of Figure 1.

The numeral 1 indicates a car having vertical side walls 2—2 and vertical end walls 40 one of which is indicated by the numeral 3, which walls serve to confine the maximum load of commercial lading.

45 Trucks, one of which is located adjacent to each end of the car, are illustrated diagrammatically by the wheels thereof, which wheels are indicated by the numerals 4—4. According to the illustrated embodiment of the present invention, the car is provided 50 with load discharging mechanism located between the trucks, said mechanism comprising doors, one of which is indicated in part of its length in Figure 1, said door bearing the numeral 5. Said doors 5 are

mounted for swinging movement about axes 55 disposed longitudinally of the car.

The mechanism and arrangement of the load discharging doors between the trucks need not be illustrated or described, inasmuch as mechanism for this purpose is well 60 known. It will be sufficient to state that the mechanism between the trucks will preferably permit the selective dumping of material either between the rails upon which the car is placed or outside of said rails. 65

Adjacent each end of the car is a wall 6 spaced inwardly from the end wall 3. This wall 6 extends upwardly between the car sides from a point adjacent the ends of the doors 5 so that the lading located between 70 the walls 6 will move toward the doors 5 when said doors are open. The wall 6 should be disposed at such an angle relative to a horizontal plane that ballast material will flow therefrom. An angle of approximately 45 degrees or greater is suitable for 75 this purpose. In the present embodiment of my invention I have shown these walls sloping upwardly toward the car ends to a point sufficient to enclose a maximum lading of 80 heavy ballast material. It will be noted that by this arrangement a space or compartment is provided at each end of the car between the end walls 3 and the intermediate walls 6 so that, if it is desired to load 85 the car with coal or like material which is lighter than ballast, a maximum load of such material may be placed in the car by loading not only the center compartment but both end compartments as well. 90

At each end of the car above the trucks is a floor indicated by the numeral 7. The details of construction of the floor 7 do not form a part of the present invention, but said floors should be so designed as to 95 permit the discharge of lading therefrom to the sides of the car outside the rails. In the illustrated embodiment of the present invention, the floor 7 may comprise sloping portions for directing lading laterally 100 of the car, said sloping portions having their apex along the line marked by the angle 8. Swinging side doors 9—9 may be provided, controlled in any preferred way for permitting lading to flow from said floor 7 to the sides of the car. Co-operating 105 with each sloping wall 6 is a reversely sloping wall 10, which walls 10—10 are pro-

vided for the purpose of supporting lading at the ends of the car, permitting the efficient discharge thereof, and for forming a suitable brace for the wall 6. Each wall 5 6 extends to a line disposed transversely of the car, which line lies near the top of the car above the corresponding truck indicated by the wheels 4—4. In the illustrated embodiment of the present invention, 10 the top of each wall 6 lies in a vertical plane substantially midway between the wheels 4—4 of its adjacent truck. It will be understood, however, that this wall may extend to any point sufficient to enclose the 15 maximum load of heaviest material.

In order to provide means for preventing the load of ballast material from falling into the end compartments of the car and also to provide for the loading of the car 20 with ballast material of different weights, I provide the upper edge of each wall 6 with a swinging partition 11, which partition is supported by means of a hinge 11', or by other preferred means. Each of said partitions 11 is adapted to occupy a position in which it is turned downward against its corresponding wall or to be turned upward to form an extension of this wall as illustrated in dotted lines in Figure 1. For the 25 purpose of holding the partition 11 in its operative position, the side walls of the car may be provided with stops indicated by the numeral 12. Latch members indicated by the numeral 13 may be provided for co- 30 operating with the stops 12 and the swinging partitions 11 thereby holding the said partitions securely in operative position.

The tops of the walls 6—6 define the limits 40 longitudinally of the car, of the lading carried centrally of the car, the outline of which lading is indicated by the numeral 14. The lower line 14 indicates a lading of the heaviest ballast material, while the upper line 14 indicates a limit of lading of lighter 45 ballast material, which is heavier than ordinary commercial lading.

In operation, when it is desired to use the car for carrying ballast or other heavy lading, said heavy lading will be deposited 50 in the car centrally thereof, being carried by the bottom portion and, if the walls 6—6 are placed at an angle less than 90 degrees, by said walls. When the car is used for carrying relatively heavy lading, the partitions 11—11 will be turned up so as to effectually confine such heavy lading between the walls 6—6. These partitions 11—11 also serve to prevent the lading which is deposited between the walls 6 from passing 55 over the upper edges of the walls 6 into the end compartments. They also minimize the danger of dropping the lading intended to be placed between the walls 6 into the end compartments. As this lading is usually 60 deposited in the car by steam shovels, care 65

lessness or inattention on the part of the steam shovel operator might result in a portion of the ballast material passing into the end compartments. When the car is to be used for the purpose of carrying a 70 commercial lading, such as coal, the entire car between the end walls 3—3 thereof may be filled with such lading, the partitions 11—11 being located in their positions along their corresponding walls 6—6 at this time. 75 In whichever way the car is loaded the lading may be discharged therefrom through the proper operation of the dumping doors.

Though a preferred embodiment of the present invention has been described in detail, it will be understood that many modifications will occur to those skilled in the art. It is intended to cover all such modifications that fall within the scope of the appended claims. 80 85

What is claimed is:

1. A car of the class described comprising a body portion having vertical side and end walls and a floor provided with load discharging means between the trucks and with 90 load discharging means over the trucks, intermediate walls extending upwardly from a point adjacent the ends of the load discharging means between the trucks, said walls dividing the car body into a central 95 compartment and end compartments, and means co-operating with the upper edge of said intermediate walls for preventing lading from falling into the end compartments. 100

2. A car of the class described comprising a body portion having vertical side and end walls and a floor provided with load discharging means between the trucks and with load discharging means over the trucks, intermediate walls extending upwardly from a point adjacent the ends of the load discharging means between the trucks, a swinging member along the upper edge of said intermediate walls, said swinging member forming an extension of its intermediate 105 wall when swung upwardly, and means for securing said swinging member in its upward position. 110

3. A car of the class described comprising a body portion having vertical side and end walls and a floor provided with load discharging means between the trucks, intermediate walls extending upwardly from a point adjacent the ends of the load discharging means, a swinging member along the upper edge of said intermediate walls, said swinging member forming an extension of its intermediate wall when swung upwardly, and a latch member for securing said swinging member in its upward position to the side walls of the car. 115 120

4. A car of the class described comprising a body portion having vertical side and end walls and a floor provided with load discharging means between the trucks and with 125

load discharging means over the trucks, wall when moved upwardly, and means for intermediate walls extending upwardly securing said movable member in its upward from a point adjacent to the ends of the position. ¹⁰

load discharging means between the trucks, ⁵ Signed at Chicago, Illinois, this 21st day a movable member along the upper edge of of July, 1924.

said intermediate walls, said movable member forming an extension of its intermediate
